BABY'S GARMENT

Jacques Cohen, New York, N. Y.

Application July 26, 1948, Serial No. 40,677

1 Claim. (Cl. 128—284)

1

This invention relates to an undergarment for infants for use especially, but not exclusively, in connection with disposable diapers and similar absorbent pads.

The primary object of the invention is the provision of a water-proof undergarment for infants which may serve as a holder for disposable diapers. Although its primary use is in conjunction with disposable diapers, it may also be used in association with conventional diapers of the non-disposable type. The disposable diapers which are most suitable for use with the undergarment herein claimed are not complete diapers in the sense of having wrap-around flaps which encircle the waistline region of the infant's body. Instead, they are relatively limited in scope, coverage and function. In essence they comprise absorbent pads which must be held in place by a garment such as the undergarment of the present application.

Another object of this invention is the provision of an undergarment of the character described having unique constructional features which make for great savings in the materials used and labor expended in producing the garment in quantity.

A further object of the invention is the provision of an undergarment of the character described which is automatically expandable and adjustable to accommodate the body of a growing infant. This undergarment also has the feature of being readily draped upon the infant's body and as readily removed therefrom.

A preferred form of this invention is shown in the accompanying drawing, in which:

Fig. 1 is a perspective view of the garment as seen from the front when worn on the person of an infant.

Fig. 2 is a similar view of said garment showing how the garment expands in size to accommodate the body of a growing child.

Fig. 3 is a plan view of the blank from which the major part of the garment is made, one end of the blank being shown folded over upon itself to form one of the pockets of the garment.

Fig. 4 is a plan view of the second blank used in the making of the garment herein claimed.

Fig. 5 is a plan view of the inside of the garment, said garment being shown spread out upon a flat plane.

Fig. 6 is a similar view of the outside of the garment.

Fig. 7 is a section on the line 1—7 of Fig. 5.

It will be seen from the drawing that the body of the undergarment herein described and

5 claimed makes use of two blanks only: A large rectangular blank 10 shown in Fig. 3, and a small three-sided blank 11, having one rounded corner, shown in Fig. 4. More precisely, this undergarment makes use of a single blank 10 and four blanks 11.

10 When the garment is made, the two end portions 10a and 10b of blank 10 are folded over to form pockets 26 (Fig. 7). In Fig. 3, portion 10b is shown folded over preparatory to the sewing operations hereinafter referred to, and portion 10a is shown before it is folded over upon its contiguous portion of blank 10. In Fig. 5, both end portions are shown folded over and sewn along their respective side edges to the side edges of the main part or body of the blank. Seams 12, 13, 14 and 15 indicate the lines of stitching which join the edges of the folded portions 10a and 10b to the edges of the main or body portion of blank 20 10.

It will be noted that the folded portions are attached only along their side edges to the main part of the blank by means of the seams above mentioned. They are free from the main part 25 of the blank along their leading edges. Hence, the pockets 26 are formed between each of the folded portions and the body part of the garment. These two pockets are disposed at opposite ends of the garment, facing each other. It is, therefore, possible to insert the two ends of an absorbent pad or disposable diaper into these two pockets. It will now be understood that this is the means by which the undergarment herein claimed accommodates and holds absorbent pads, 30 disposable diapers, and similar articles.

35 Blanks 11 are sewed to blank 10 by means of the same seams 12 to 15 inclusive by which the sides of the flaps are sewn to the body part of blank 10. This will clearly be seen in Fig. 5. It 40 will be seen that when these blanks 11 are sewn or incorporated into the garment they take on the appearance and function of side or wrap-around flaps with respect to the body of the wearer. Flaps 11a and 11b may be designated as the front 45 flaps of the garment and flaps 11c and 11d may be designated as the rear flaps. (See Fig. 1.) A binding 20 is sewn to all marginal edges of the garment to reinforce said edges and to prevent raveling. It will be noted that flaps 11a and 11b 50 are spaced, respectively, from flaps 11c and 11d. A pair of elastic members 25 are attached to the edges of the garment in the two areas which space flaps 11a and 11b from flaps 11c and 11d. Binding 20 is the means by which these two elastic members are affixed to said garment edges.

They are sewn to the garment edges under tension and hence they cause a gathering or ruffling of the garment in the area between the two pockets formed therein. This is best seen in Figs. 5 and 6.

When the garment herein described is draped upon the body of the infant the ruffled portion of the garment covers the crotch area, the elastic edges 25 encircling the thigh. The end of the garment which includes folded portion 10b becomes the front of the garment and the end which includes folded portion 10a becomes the back of the garment. Flaps 11c and 11d which are attached to the front of the garment extend backwardly around the sides of the infant's body to the back of the garment. Flaps 11a and 11b, attached to the back of the garment, extend forwardly around the sides of the infant's body to the front of the garment, and it will be noted that they overlie flaps 11c and 11d respectively. This is especially true when the garment is in extended or enlarged condition, as pictured in Fig. 2. When the garment is in fully contracted condition, flaps 11a and 11b may by-pass or extend beyond flaps 11c and 11d without overlying any part of said latter flaps.

To hold the garment in its draped position about the body of the wearer, a pair of snap-fasteners is provided. The male members 21 of said snap-fasteners are affixed to flaps 11a and 11b, which may be designated as the front flaps of the garment although they are attached to the back thereof. The female members of said snap-fasteners, indicated in the drawing by means of reference character 22, are affixed to a relatively wide elastic strip 23 which is attached, intermediate its ends, to the front of the garment. Stitches 24 indicate the means by which said elastic strip or band is attached to the front of the garment. It will be seen that this elastic band extends transversely of the front of the garment and its female fastening members are therefore adapted to engage the male fastening members on the front flaps of the garment. Since this elastic band is the sole means that holds the garment about the body of the wearer, it will be appreciated that the garment is extensible or expandable to accommodate bodies of varying girths, and especially the body of a growing infant. Besides, this relatively wide elastic band may obviate the use of a bellyband since it will apply the necessary pressure in the region of the navel of the infant.

The material of which the garment herein described is made should be a water-proof material, resistant to urine acids. In its preferred form, the garment is made of a rubber-coated fabric, but other water-proof fabrics or substitutes therefor may also be used.

It will be seen that as the infant grows, not only does the waist portion of the garment accommodate the greater girth, but the leg openings also are incidentally enlarged to accommodate heavier thighs.

A preferred form of the invention has above been described. The invention is sufficiently broad in scope, however, to cover other forms or modifications of the form herein described. 10 The garment may be modified, for instance, by substituting other fastening members for the snap-fasteners shown in the drawing.

Having thus described my invention, what I claim as new and desire to secure by Letters Patent, is:

An undergarment of the character described comprising a substantially oblong blank of fabric, each end thereof being folded upon itself, the coincident side edges of said blank and of the corresponding folded-over end portions being secured together to form a pocket at each end on the inside of said garment, a substantially right triangular blank of fabric secured to said side edges adjacent each said end with one side of a triangle aligned with the folded end edge on each side to form a continuation of said edge, said triangular blanks on each side, being spaced apart, the hypotenuse of the triangles on each side of said blank facing each other, the portion of the oblong blank which lies between and is unsecured to said triangles constituting the crotch portion of the garment, each side edge only, of said crotch portion being provided with an elastic member to cause a gathering of the material of said crotch portion; an elastic fastening member extending transversely of said garment near one end thereof on the outside of said garment and having its midsection fixedly secured thereto, a snap fastener element on each end of said elastic member releasably engageable with companion snap fasteners on each of the triangular blanks.
